UNITED STATES PATENT OFFICE

96,629

DESIGN FOR A PIN GAME BOARD

Kenneth C. Shyvers, Chicago, Ill.

Application December 27, 1934, Serial No. 54,619

Term of patent 7 years

To all whom it may concern:

Be it known, that I, Kenneth C. Shyvers, a citizen of the United States, residing at Chicago, in the county of Cook and State of Illinois, have invented a new, original, and ornamental Design for a Pin Game Board, of which the following is a specification, reference being had to the accompanying drawing, forming a part thereof.

I claim:—

The ornamental design for a pin game board as shown.

In testimony whereof, I affix my signature.

KENNETH C. SHYVERS.
